Canton, Ohio, a corporation of Ohio

Application December 23, 1937, Serial No. 181,281

12 Claims.

(Cl. 62—5)

- This invention relates to refrigerating apparatus and more particularly to control mechanism for such apparatus. In absorption refrigerating apparatus as previously constructed the control mechanism has been located in the lower part of the cabinet adjacent the boiler thereby necessitating an elongated flexible connection between the manual control means and the regulating device for the control mechanism. This arrangement resulted in a difficult assembly due to the necessity for leading a flexible control cable from a point adjacent the evaporator to the boiler without sharp bends. Also the flexible cable encased in a coiled wire housing introduced a large frictional load on the control adjusting mechanism with the result that the manual regulating knob—usually mounted adjacent the evaporator—was difficult to operate. A flexible cable connection between the manual adjusting knob and the thermostatic control mechanism introduced a very troublesome adjusting problem due to the fact that slight elongation of the cables, slippage on the pulleys, or slipping of the cable housing would destroy the calibration of the sensitive temperature range adjusting mechanism for the thermostatic bellows. If the gas valve and thermostatic controlling mechanism of an absorption refrigerating system is mounted on or adjacent the boiler it is apt to be injured by the excessive temperature conditions prevailing at these points. The delicate bellows and springs of the thermal control and the accurately formed gas valve ports may warp or lose their temper if subjected to high temperatures. Also the bellows is filled with a fluid which expands and contracts with small temperature changes. If the bellows is positioned in a high temperature zone it will not respond accurately to temperature changes in the cooling unit; this was further complicated by the fact that the capillary tube connecting the bellows and the bulb mounted on the evaporator had to be of extreme length and well insulated. However, even with the greatest care, the calibration of the control mechanism may be destroyed by heating, bending or elongation of the capillary tube. Accordingly, it is an object of this invention to arrange a refrigerator control mechanism in a position not subjected to temperature extremes, permitting a direct positive mechanical connection between the adjusting knob and the temperature range adjusting mechanism, and per-

mitting a short capillary connection between the bellows in the control mechanism and the thermostatic control bulb in the food compartment.

It is a further object of this invention to provide a control mechanism which is simply mounted and is positioned to be serviced with a minimum of difficulty.

It is another object of this invention to mount a control mechanism on a refrigerating apparatus in such fashion that the entire system including the control may be tested as a unit and may then be mounted in a cabinet as a unit.

It is a further object of this invention to provide a control mechanism having a manual adjusting knob which may be operated with a minimum of effort on the part of the operator.

It is a further object of this invention to provide a control mechanism adapted simultaneously to control a gas valve and an electric switch which regulate the supply of energy to an absorption refrigerating system.

It is a further object of this invention to combine a novel defrosting mechanism with a novel refrigerating control mechanism.

Other objects of the invention reside in various arrangements and construction of parts which will be apparent as the description proceeds when taken in connection with the accompanying drawings, in which:

Figure 1 is a partial sectional view of a refrigerating apparatus embodying my invention.

Figure 2 is a horizontal sectional view taken along the line 2—2 of Figure 1 and looking in the direction of the arrows.

Figure 3 is a partial sectional view on an enlarged scale of my control mechanism.

Referring now to the drawings and first to Figures 1 and 2 thereof, it will be seen that I have disclosed a continuous three-fluid absorption refrigerating system of the type utilizing a gas burner to generate refrigerant and a motor-driven fan to circulate an inert gas. The refrigerating system comprises a boiler B, an analyzer A, a rectifier R, a condenser C, an evaporator E, a gas heat exchanger H, an absorber D, and a circulating fan F driven by a motor M. These elements are suitably connected in circuit to form a complete refrigerating system.

Heat is applied to the boiler B from a suitable gas burner G of conventional design and provided with suitable safety-cut-off means. The boiler B contains a solution of refrigerant in an absorbent, preferably ammonia in water, which liberates ammonia vapor when subjected to heat.

Ammonia vapor generated in the boiler B passes upwardly through the analyzer A in counterflow to strong absorption liquid supplied in a manner to be described hereinafter. The refrigerant vapor exits from the analyzer A through a conduit 11 which is connected to the condenser C and includes a rectifier R. Entrained water vapor is condensed in the rectifier R and is returned to the analyzer A. The condenser C is preferably a tubular finned air-cooled type. The refrigerant vapor is liquefied in the condenser C and is discharged through a conduit 12 into a finned box cooling conduit 13 forming the upper part of the evaporator E. The liquid refrigerant flows downwardly through the evaporator by gravity counter to a stream of an inert pressure equalizing medium, such as hydrogen or nitrogen, which is supplied from the gas heat exchanger H through a conduit 14. A suitable drain for the evaporator is indicated at 14'.

The liquid refrigerant vaporizes into the pressure equalizing medium in the evaporator to produce refrigeration and the resulting mixture of refrigerant vapor and pressure equalizing medium exits from the evaporator through the box cooling conduit 13 and the conduit 15 into the gas heat exchanger H.

The rich mixture is conveyed from the gas heat exchanger H through a conduit 16 to the lower end of the absorber D which is preferably of the finned tubular air cooled type. The vapor-gas mixture passes upwardly through the absorber D in counterflow to weak absorption liquid flowing downwardly by gravity whereby the refrigerant vapor is absorbed in the liquid and the pressure equalizing medium exits from the absorber D through the conduit 17 into the suction inlet of the circulating fan F which is driven by a motor M, preferably of the hermetically sealed type. The gas is discharged under pressure through the conduit 18 into the gas heat exchanger. The weak gas returns to the evaporator E from the gas heat exchanger H through the conduit 14 previously described.

Weak liquor formed in the boiler B as a result of generation of refrigerant vapor exits therefrom through the conduit 19, liquid heat exchanger 20, and conduit 21 which communicates with the upper end of the absorber D at the point at which the conduit 17 connects with the absorber D. The strong liquor formed in the absorber D exits from the lower end thereof through a conduit 22, the liquid heat exchanger 20 and a conduit 23 which discharges into the analyzer A. A conduit 24 connects the gas discharge conduit 18 with the weak liquor conduit 21 at a point below the liquid level in the boiler-analyzer system whereby the weak liquor is elevated into the upper end of the absorber by gas-lift action.

The refrigerating apparatus just described is housed within a suitable insulated cabinet 30 which is provided with a suitable door 31. The evaporator E is positioned in the top central portion of a food compartment 32. The refrigerating apparatus with the exception of the evaporator E and the gas heat exchanger H is housed within a space 33 extending along the bottom of the cabinet 30 beneath the compartment 32 and vertically along the rear thereof.

The vertical portion of the space 33 forms an air-cooling flue for various heat rejecting portions of the system. Cooling air enters the space 33 through suitable openings in the bottom of the cabinet 30 and also if desired through suitable louvers in the rear panel 34 of the cabi-

net. The cooling air flows upwardly over the air-cooled absorber D, the rectifier R, and the condenser C and exits through suitable openings formed in the top of the cabinet 30.

The entire refrigerating apparatus is mounted upon a suitable framework, not shown, and is designed to be inserted as a unit into the cabinet 30 after which the rear plate 34 is mounted on the apparatus. A suitable window 40 is formed in the rear wall of the cabinet 30 and is designed to be closed by an insulating block 41 which encloses the upper part of the gas heat exchanger and the connections to the evaporator and is carried by the refrigerating apparatus. The insulating block 41 and the insulated rear wall of the cabinet 30 are formed with a vertically extending channel 47 which receives the gas heat exchanger H. The open face of the channel 47 is closed by an insulating block 42 which is shaped to embrace the gas heat exchanger and to seal the channel.

The control mechanism 50 for the gas burner G and the motor M is rigidly attached to the block 41 in any suitable manner. The control mechanism is adjusted by means of a manually actuated knob 51 rotatably mounted in any suitable manner in a control panel 52 which is attached to the casing of the evaporator E and extends thereabove completely concealing the box-cooling evaporator section 13. A control shaft 53 extends rearwardly from the knob 51 above the finned conduit 13, through the insulating block 41, and carries on the outer end thereof of a beveled gear 54 which meshes with a beveled gear 54' rotatably mounted on the control mechanism 50.

The control mechanism carries thereon a valve 55 which controls the supply of gas to the burner G. Gas is led into the valve 55 from a conduit 48 and is conducted from the valve to the burner G by a conduit 49.

Products of combustion from the burner G pass through the boiler B and are conducted therefrom by a conduit 45 into a distributing flue 46. The flue 46 is flared upwardly from its junction with the conduit 45 and terminates in an elongated discharge mouth adjacent the top portion of the cabinet 30. Flue 46 is positioned laterally of the control mechanism 50 to prevent hot products from impinging on the control mechanism and the gas valve.

Referring now to Figure 3, it will be seen that our control mechanism comprises the casing 50 which rigidly carries on one end thereof the gas valve 55 which is of a conventional "on" and "off" type and is provided with the usual pilot by-pass, not shown. The gas valve 55 is provided with an elongated actuating shaft 56 which extends into the housing 50 and is suitably guided therein for reciprocatory motion. A small coil spring 44 positioned within the housing 50 urges the valve 55 to the closed position.

A suitable bellows 57 is slidably mounted in a guide ring 58 which is rigidly mounted in the housing 50 in any suitable manner. The bellows 57 is provided with a hollow extension 59 which is slidably mounted in a bushing 60 threaded into the wall of the casing 50. A stiff spring 61 is interposed between the bushing 60 and a plate 62 which abuts the end of the bellows 57 and the guide ring 58. The hollow conduit 59 communicates through a capillary tube 63 with a bulb element 64 which is mounted on any suitable portion of the evaporator to be controlled. The bulb 64, conduit 63, conduit 59, and bellows 57 75

- are charged with a suitable fluid which expands and contracts in response to temperature changes inducing a corresponding expansion and contraction of the bellows 57.
- 5 The end of the bellows 57 remote from the conduit 59 is provided with a bearing pivot 58' which seats in a cup 65 rigidly carried by an actuating arm 66. The actuating arm 66 is pivotally mounted at 67 upon the interior wall of the casing 50.
- 10 The bevel gear 54' is rigidly carried by a shaft 68 which is rotatably mounted in the end wall of the housing 50. A suitable collar 68' prevents the shaft 68 from shifting laterally with respect to the housing 50. The end of the shaft 68 within the housing 50 is threaded and receives an adjusting nut 69 which is provided with an extension engaging a guide rib 70 formed integrally with the housing 50 to prevent rotation of the nut 69 with the shaft 68. A suitable spring 71 is interposed 15 between the nut 69 and the actuating arm 66 whereby rotation of the shaft 68 adjusts the resistance against which the bellows 57 must expand.
- 15 The free end of the actuating arm 66 is provided with a conical member 72 which bears in a depression in a spring retaining cup 73 receiving one end of a snap spring 74. The opposite end of the spring 74 is received within a spring-retaining cup 75 which has a depressed portion 20 receiving a conical element 76 carried by a follower arm 77. The follower arm 77 is carried by a U-shaped supporting bracket 78, only half of which is shown, pivotally mounted at 79 to fixed support 80. The support 80 also carries an adjustable limit stop 80' for the arm 66. It will be seen that the snap spring 74 is positioned between the arms of the U-shaped bracket 78. The arm 77 is positioned to engage the valve actuating shaft 56 at one extreme limit of its movement 25 and to engage one element 81 of a make and break switch 82 in the other extreme limit of its movement.
- 25 The snap mechanism is shown in position to open the valve 55 and to allow the switch 82 to close. In the opposite position of the snap mechanism the spring 44 closes the valve and the follower arm 77 engages the element 81 to open the switch 82.
- 30 The switch 82 is connected to a line wire 83 and to a wire 84 which is connected to the circulating motor M.
- 35 The actuating arm 66 is provided with a latch member 85 which is adapted to engage a latch-keeper member 86 formed on the end of a defrosting lock-out arm 87 which is pivotally mounted in housing 50 at 88. A small torsion spring 89 urges the lock-out arm 87 in a counter-clockwise direction as viewed in Figure 3. Counter-clockwise rotation of the arm 87 is prevented 40 by engagement with the plate 62 previously described. The end of the arm 87 engaging the plate 62 is formed with a cam surface 91 which will cause clockwise rotation of the arm 87 when the plate 62 is shifted to the left as viewed in 45 Figure 3.
- 45 In operation, the bellows 57 expands and contracts in response to temperature changes in the evaporator E and cycles the switch 82 and gas valve 55 in a manner to maintain the evaporator within predetermined temperature limits. The temperature limits in the evaporator are determined by the compression of the spring 71 which is determined by the setting of the knob 51 through the agency of the gears 54 and 54' 50 and the adjusting shaft 53.
- 50 Defrosting is accomplished by turning the knob 51 to the defrosting position, suitably marked on the panel 52, and then returning the knob to any normal control point, also suitably marked on the panel 52. Movement of the knob 51 to the defrosting position advances the nut 69 to such an extent that the spring 71 will rock the arm 66 in a counter-clockwise direction, as viewed in Figure 3, a distance sufficient to cause the latch member 85 to engage behind the latch-keeper 86. Under these conditions the bellows 57 is locked 55 against movement in a direction to swing the arm 66 in a clockwise direction, as viewed in Figure 3, to open the valve 55 and to close the switch 82, and the evaporator temperature rapidly increases 10 to a value high enough to melt frost therefrom. As the evaporator warms up the bellows 57 expands to the left, as viewed in Figure 3, and compresses the stiff spring 61. The plate 62 shifts to 15 the left with the slidably mounted end of the bellows and releases the engagement between the members 85 and 86 by coaction with the cam surface 91 when the evaporator has defrosted whereupon the bellows is released and the machine returns to normal operation.
- 20 The valve is positioned to be swept by the warm air flowing upwardly in the space between the panel 34 and the rear wall of the storage compartment due to the heat rejected by the absorber, condenser, and rectifier. The boiler flue 25 system also induces a warm air flow upwardly through the cooling flue. However, the valve is not subjected to hot products of combustion as these are discharged laterally of and above the casing 50. The warm air stream prevents condensation of water vapor in the gas valve but is not sufficiently hot to injure the valve and control mechanism or to impair the calibration of the control mechanism.
- 30 The control mechanism is adjusted from the 35 control knob by a direct and positive connection whereby there is no possibility of loss of adjustment for the control mechanism by reason of slipping or elongating cables. Also the operator need only supply sufficient force to the knob 51 to advance or retract the nut 69 and he need not overcome the frictional resistance inherent in a long 40 encased cable which follows an irregular path.
- 35 While we have illustrated and described only a single embodiment of our invention, it is to be 45 understood that it is capable of expression in other forms and constructional variations without departing from the spirit of the invention and the scope of the appended claims.
- 45 We claim:
- 50 1. Refrigerating apparatus comprising a storage compartment, a window formed in the rear wall of said compartment, a cold-producing mechanism including a cooling unit adapted to be inserted into said compartment through said window, a closure member for said window carried by said cold-producing mechanism rearwardly of said cooling unit, and control mechanism for said cold-producing mechanism mounted on said closure member.
- 55 2. Absorption refrigerating apparatus comprising a boiler, a condenser, an evaporator, an absorber, means interconnecting said elements to form an absorption refrigerating system including a pressure equalizing medium circuit between said absorber and said evaporator, power-driven means for circulating a pressure equalizing medium through said pressure equalizing medium circuit, means for applying heat to said boiler, control means for said apparatus mounted at the 60
- 65 70
- 70 75

- level of said evaporator, said control means including means simultaneously operative to control said power-driven circulating means and said means for applying heat to said boiler.
3. Absorption refrigerating apparatus comprising a cooling compartment, a cooling duct extending vertically in the rear of said compartment, a mechanism chamber beneath said compartment, a boiler in said chamber, an absorber 10 in said chamber and beneath said cooling duct, a condenser in said duct, a cooling unit in said compartment, means connecting said boiler, absorber, condenser, and cooling unit in circuit to form a refrigerating system, means for applying 15 heat to said boiler, means for conveying products of combustion from said boiler to an area adjacent the top of said cooling duct, and control means mounted in said duct at the level of the cooling unit and positioned remotely from said 20 combustion products discharge area.
4. Absorption refrigerating apparatus of the type involving a boiler and a cooling unit within a storage compartment said apparatus including means to heat said boiler, control means for said 25 boiler heating means positioned at the level of said cooling unit, and means shielding said control means from temperature conditions prevailing at said boiler and said cooling unit.
5. Refrigerating apparatus comprising an insulated storage compartment, an evaporator mounted in said compartment, a finned box-cooling evaporator conduit mounted on the top 30 wall of said evaporator, an upstanding front panel on said evaporator arranged to hide said finned box-cooling conduit, control mechanism for said apparatus mounted on the rear wall of said cabinet at the level of said box-cooling conduit, an adjusting element for said control mechanism 35 mounted on said panel, and a direct mechanical connection extending above said conduit between said adjusting element and said control mechanism.
6. Absorption refrigerating apparatus comprising an insulated cabinet, a mechanism compartment associated with said cabinet, an evaporator mounted within said cabinet, means 40 in said compartment for supplying refrigerant to said evaporator including a boiler, an absorber and a condenser, means for heating said boiler, control means for said boiler heating means 45 mounted in said compartment in position to be swept by warm air flowing therethrough from said absorber, and means shielding said control means from high temperature conditions existing in the vicinity of said boiler.
7. Absorption refrigerating apparatus comprising an insulated cabinet, a mechanism compartment associated with said cabinet, an evaporator mounted within said cabinet, means 50 in said compartment for supplying refrigerant to said evaporator including a boiler, an absorber and a condenser, means for heating said boiler, control means for said boiler heating means 55 mounted in said compartment in position to be swept by warm air flowing therethrough from said absorber, means shielding said control means from high temperature conditions existing in the vicinity of said boiler, means mounted in said compartment for adjusting said control 60 means, and a direct mechanical connection be-

tween said control means and said adjusting means.

8. Absorption refrigerating apparatus of the type including a boiler, a combustible fuel burner for heating the boiler and an insulated cabinet 5 housing an evaporator comprising in combination a removable insulated panel in said cabinet adjacent said evaporator, means for controlling the supply of fuel to said boiler carried by said panel, means within said cabinet for adjusting 10 said control means, means for shielding said control means from hot products of combustion discharged by said boiler heater, and means for flowing a warm air current over said control means.

9. Refrigerating apparatus comprising a cabinet, a cooling unit in said cabinet, control mechanism for said cooling unit mounted on the rear wall of said cabinet at the level of said cooling unit and offset therefrom, adjusting means 20 for said control mechanism mounted adjacent said cooling unit, a drive shaft actuated by said adjusting means, and gearing connecting said drive shaft and said control mechanism.

10. Refrigerating apparatus comprising a cabinet, a cooling unit in said cabinet, control mechanism for said cooling unit mounted on the rear wall of said cabinet, said control means including an adjusting shaft extending generally parallel to the plane of the rear wall of said 30 cabinet, adjusting means for said control mechanism mounted adjacent said evaporator, an adjusting shaft connected to said adjusting means and angular motion transmitting mechanism connecting said shafts.

11. Absorption refrigerating apparatus comprising an insulated cabinet, a mechanism compartment associated with said cabinet and including a portion extending along the rear wall thereof, an evaporating unit mounted in said cabinet, means for supplying refrigerant to said evaporating unit including a boiler and an air-cooled heat rejecting unit mounted in said compartment, said heat rejecting unit being arranged to discharge warmed air upwardly along the rear 45 wall of said cabinet, control mechanism for said apparatus mounted in said compartment in position to be swept by the warm air discharged from said heat rejecting unit.

12. Absorption refrigerating apparatus comprising an insulated cabinet, a mechanism compartment associated with said cabinet and including a portion extending along the rear wall thereof, an evaporating unit mounted in said cabinet, means for supplying refrigerant to said evaporating unit including a boiler and an air-cooled heat rejecting unit mounted in said compartment, said heat rejecting unit being arranged to discharge warmed air upwardly along the rear wall of said cabinet, a gas burner for heating said boiler, a gas valve for controlling said burner mounted in said compartment above said heat rejecting element, means in said compartment for operating said gas valve in response to the thermal condition of said evaporating unit, and means for conducting waste products of combustion from said boiler to waste in a path thermally remote from said gas valve and control means.
